UNITED STATES PATENT OFFICE

2,509,844

SASH ADJUSTER AND LOCK

Thomas B. Saner, Phoenix, Ariz.

Application February 6, 1947, Serial No. 726,861

2 Claims. (Cl. 292—63)

1

This invention relates to improvements in window sash adjustors and locks.

An object of the invention is to provide an improved window sash adjustor and lock construction which will be adjustably supported upon a sash frame to automatically hold the sash in the desired adjusted opened position.

Another object of the invention is to provide an improved window sash adjusting and locking device which will be adjustably supported upon a window sash for holding the window in any desired adjusted open position, and for automatically locking the window sash when it is disposed in its closed position.

A further object of the invention is to provide an improved window sash adjusting and locking device which will be entirely automatic in operation, the same being highly efficient and relatively inexpensive to manufacture and produce.

Other objects will appear as the description proceeds.

In the accompanying drawings which form a part of this application,

Figure 1 is a front elevation of a window frame with window sashes disposed therein, showing the improved window adjusting and locking device supported in position on the lower sash frame;

Figure 2 is a front elevation of a window frame being partly broken away and in section with upper and lower window sashes disposed therein, the lower sash shown partly raised and supporting the adjusting and locking device thereon;

Figure 3 is an enlarged detail view partly in section of a portion of a window frame and window sash showing the adjusting and locking device in locked position;

Figure 4 is an enlarged detail front view of a portion of a window frame and window sash showing the adjusting and locking device in position for holding the window sash in raised or open position;

Figure 5 is a front elevation of the improved window adjusting and locking member;

Figure 6 is an edge view of the improved window adjusting and locking member;

Figure 7 is a sectional view taken on the line 7—7 of Figure 5, and

Figure 8 is a view taken on the line 8—8 of Figure 2.

Like characters of reference are used throughout the following specification and the accom-

2
panying drawings to designate corresponding parts.

In carrying out the invention, there is provided an improved form of window sash adjusting and locking device. For purposes of illustration, there is shown a window frame generally designated by the reference numeral 1, and an upper sash frame 2 and lower sash frame 3 vertically slidably therein, being suitably glazed at 4 and 5 respectively.

A locking notch or seat 6 is cut into the side wall of the window frame 1 in its inner surface adjacent its lower end, as clearly illustrated in Figures 1, 2 and 3 of the drawings. The upper portion 7 of said notch or seat 6 forms an angled locking shoulder against which the upper end of a locking member hereinafter described will engage, while the outwardly and downwardly extending side 8 of the notch or seat 6 will be engaged by the upper side of said locking member when the lower window sash or frame 3 is in fully closed position.

The improved adjusting and locking member comprises a substantially rectangular shaped flat plate 9 which will be formed with an upstanding top flange 10, an upstanding bottom flange 11, and a connecting upstanding side flange 12. Vertically extending contact cams or bearing lips 13 and 14 are integrally formed at the juncture points of the top and bottom flanges 10 and 11 with the opposite ends of the side flange 12, serving to engage the inside edge or surface of the window frame 1 when the locking member and lower window sash frame 3 is in raised or open position.

The body of the adjusting and locking member 20 is provided with the spaced parallel inwardly and downwardly extending slots or guideways 15 and 16, said slot or guideway 15 being also formed with a spur or extension slot 17 adjacent its upper end extending inwardly through the member 9, and is formed with an annular or arcuate seat portion 18 at its innermost end.

Positioning screws or lugs 19 and 21 will be placed through said slots or apertures when the lower window sash frame is in closed position with the adjusting and locking member or plate 9 seated in the locking notch or seat 6, to be received respectively in the annular seat portion 18 of the spur slot 17 and in the upper end of the slot 15, as clearly illustrated in Figure 3 of the drawings.

The screws 19 and 21 will be screwed into the lower sash frame 3 far enough to firmly support

the adjusting and locking plate or member 9, but will allow for sufficient play or movement of said member 9, as the same moves up and down with the lower sash frame 3 to frictionally engage the inner surface of the window frame 1, thereby frictionally clamping against the window frame with the contact or bearing lips 13 and 14 to effectively and efficiently hold the lower window sash frame in the desired adjusted open position.

The mode of operation of the improved sash adjustor and lock will be more fully explained as follows: When the lower window sash 3 is in its fully closed position, the locking member or plate 9 will be moved laterally until it is received in the locking notch or seat 6 formed in the adjacent side wall of the window frame 1, as clearly illustrated in Figure 3 of the drawings, thereby positively preventing anyone on the outside of the window sash from releasing the locking member so that the window sash may be raised.

When it is desired to raise the window, the locking plate or member 9 will be moved laterally toward the right as seen in Figure 3 of the drawings, causing the plate to assume a vertical position, as shown in Figure 4 of the drawings. The window may then be raised to the desired height, and due to the inclination of the parallel extending slots 15 and 16 cooperating with the securing screws 19 and 21, movement of the window in a downward direction will cause a lateral movement of the locking plate or member 9 toward the left or toward the adjacent inside surface of the window frame 1, thus causing the shoulders 13 and 14 at the ends of said plate or member 9 to frictionally engage the adjacent inner surface of said window frame to frictionally hold the sash in the desired adjusted open position. Obviously, the amount of friction between the locking plate or member 9 and the adjacent inner surface of the window frame may be readily overcome when it is desired to lower the window or sash frame, by merely pulling down on the sash.

From the foregoing description, it will be apparent that there has been devised and provided a highly efficient form of sash adjustor and lock for window constructions.

While the preferred embodiment of the instant

invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

10. Means for retaining a sash frame in adjusted open positions in a window frame; comprising a pair of upper and lower vertically spaced and aligned outwardly extending lugs on the sash frame adjacent the window frame, a locking plate 15 adjustably disposed on the sash frame and having a pair of upper and lower parallel angularly disposed guideways slidably supported on the lugs, outwardly extending flanges on the top and bottom of the plate, a locking flange on one side of 20 the plate connected with said first mentioned flanges, a pair of cams extending outwardly in diverging directions at the connecting points between the flanges and adapted to frictionally bear against the window frame to prevent downward travel of the sash frame.
25. The combination of claim 1, wherein said window frame is provided with an inwardly extending angular downwardly facing seat and means is provided for positioning said locking plate in the seat preventing upward movement of the sash frame, said means including a lateral extension slot disposed on the upper guideway in the opposite direction from the locking flange, said extension slot terminating in an arcuate seat 30 to lockingly engage the upper lug.

THOMAS B. SANER.
